UNITED STATES PATENT OFFICE.

GEORGE HOWLETT DAVIS, OF BROOKLYN, NEW YORK.

ELECTRIC PERFORATING-MACHINE.

No. 832,849.

Specification of Letters Patent.

Patented Oct. 9, 1906.

Application filed April 22, 1901. Serial No. 57,000.

To all whom it may concern:

Be it known that I, GEORGE HOWLETT DAVIS, a citizen of the United States, residing in the borough of Brooklyn, county of Kings, city and State of New York, have invented certain new and useful Improvements in Electric Perforating-Machines, of which the following is a specification, reference being had therein to the accompanying drawings, in which—

Figure 1 is a perspective view of the machine; Fig. 2, a side elevation of a portion thereof; Fig. 3, a plan view of that portion of the machine shown in Fig. 2; Fig. 4, a vertical longitudinal section of the record-blank-feeding mechanism; Fig. 5, a vertical longitudinal section showing the stencil-support and feeding means and the punch-controlling means; Fig. 6, a detail view showing the automatic means for releasing the swinging stencil-support; Fig. 7, a detail of the means for removably mounting the stencil-roll; Fig. 8, a plan view of the adjustable guides for the record-blanks; Fig. 9, a transverse section on the line 9-9 of Fig. 8; Fig. 10, an end view of a pair of the gripping-bars of the record-blank-feeding aprons; Fig. 11, a side elevation of one end thereof, the apron-guide being shown in section; and Fig. 12, a detail plan of the latch device for holding the swinging stencil-carrying frame.

This invention relates to new and useful improvements in that class of machines for perforating music-sheet paper for use with automatic musical instruments covered by my Patent No. 659,053, dated October 2, 1900, in which reciprocating punches are selected and controlled by means of electrically-actuated devices, these latter devices being controlled by a punch-selecting medium in the form of a pattern-sheet or a perforated stencil which is passed between a contact-bar and a series of selector-fingers.

One of the objects of this invention is to provide a means for comparing the record-blanks with the pattern-sheet. In one embodiment of the invention the stencil-sheet or other punch-selecting medium or pattern after it has passed between the selector-fingers and the contact-bar will be caused to move with the perforated records in such a position that the note-perforations or other selector-finger-operating means of the stencil will register with the corresponding note-holes in the record-strip, whereby the records may be readily compared by the attendant

or operator with the original and imperfections noted.

Another object of the invention is to provide a stencil or pattern-feeding device and means for operating it in advance of the movement of the mechanism for drawing the record-blanks through the machine.

A further object of the invention is to provide means for throwing out of operation the punch selecting and locking mechanism and to further provide in this connection means for automatically throwing this mechanism out of operation at the end of the stencil or pattern-sheet.

Other important objects, novel features of constructions, and combinations of parts will be hereinafter described.

Referring to the various parts by numerals, 1 designates the table or support, upon which are mounted the standards 1^a, which carry at their upper ends the horizontal transverse main shaft 2. On this shaft are mounted the eccentrics 2^a, which are connected by the pitmen 2^b to the ends of the punch-carrying bar 4 to vertically reciprocate said bar during the rotation of the shaft, as fully set forth in my Patent No. 659,053, hereinbefore referred to.

The record-blanks 5 are wound on transverse horizontal shafts, which are removably mounted in a frame 6, located at the rear of the table 1. This frame consists of two lower longitudinal bars 6^a, which are provided with notches in their upper edges, in which notches are journaled the ends of the horizontal transverse shafts, which carry the record-blanks. Above the lower bars 6^a and parallel therewith is a second set of similar bars 6^b, which are provided with notches in their upper edges to receive the ends of the second series of parallel transverse shafts, on which are wound record-blanks. The record-blanks are unrolled from the shafts and drawn forward under the punches, said blanks being brought together one above the other before they reach the punches, suitable pressure-rolls being provided to hold them in close contact with each other as they pass under the punches.

To accurately guide the superposed record-blanks through the punching mechanism to the endless apron-feed mechanism, the longitudinal guides 100 are provided, one of said guides being near each side edge of the table to guide the longitudinal edges of the record-blanks. These guides are formed of angle-

iron bars, one member of each bar forming the inward-extending horizontal bed-support, the other member extending upward from the outer edge of the horizontal member and forming a guide for the paper strips. The bed-pieces 101 loosely rest on the horizontal members of the guides and extend across the space between the vertical members thereof. There are two sets of guides—one to properly direct the paper to the punches and one to guide it from the punches to the feeding mechanism. Each bar is provided with a depending internally-threaded lug 102 near each end thereof. Extending across the table 1 and mounted in suitable bearings are transverse shafts 103, which pass through corresponding lugs on the guides 100. The lugs on the bars near one edge of the table are threaded in one direction, while those near the other edge of the table are threaded in the opposite direction, and the shafts 103 are correspondingly threaded where they pass through the lugs, so that by simultaneously rotating the shafts the guides will be moved inward or outward an equal distance, depending on the direction of rotation of the shafts. To simultaneously and synchronously rotate these shafts, a beveled gear is secured on the corresponding end of each shaft, and a longitudinal shaft 104 is mounted on the table and is provided with a series of gears, which mesh with the gears on the shafts 103 and are arranged to rotate said shafts all in the same direction. A suitable operating-handle is secured to one end of the shaft 104, whereby it may be conveniently rotated. The advantages of these guides will be readily seen. As the records vary in width according to the range of the musical composition it is desired to reproduce, it is very desirable to provide means for quickly and accurately centering the record-blank with respect to the punches. After the guides have been adjusted the bed-pieces of the desired width are put in place on the horizontal members of the angle-iron guides. This form of guiding mechanism is particularly advantageous when guiding superimposed webs of paper through the perforator. In such a case the webs are liable to get out of alignment and to shift with relation to each other. My form of guiding mechanism completely avoids this.

Rigidly secured to the table 1 and extending forward therefrom is a pair of horizontal supports, in which are journaled the horizontal shafts of the upper and lower feed-aprons. These feed-aprons are geared together and are driven from the main shaft 2 by means of suitable mechanism, which gives to said aprons a step by-step motion. This mechanism consists of the ratchet-wheel 42, which is secured on the outer end of shaft 11 of the upper feed-apron. Engaging this ratchet-wheel is a pawl 44, carried

by a pivoted lever 45, said lever being vibrated by means of an eccentric 47, whose strap is connected by a rod 46 to the upper end of the lever. It will thus be seen that as the main shaft 2 rotates the aprons will be given a step-by-step motion to feed the record-blanks forward, as fully set forth in my Patent No. 659,053.

Connecting the side chains 39 of the upper apron are a series of transverse rigid clamping-bars 48, which are equal distances apart, and connecting the chains 40 of the lower apron are similar transverse rigid bars 49. On the outer surface of these latter bars are secured rigid cylindrical gripping-bars 50, which clamp the record-strips against the bars 48 of the upper apron. These cylindrical gripping-bars are rotatably adjustable in order to present a new gripping-surface to the paper whenever the bar becomes so worn that it fails to grip the strips with sufficient pressure. The reduced ends of these cylindrical bars are adjustably clamped in boxes 57, carried by the bars 49. If desired, these cylindrical bars may be loosely mounted in the boxes 57, so that they will be free to easily rotate and to thereby distribute the wear around the bar. The bars 48 and 49 are provided on their inner sides near their ends with antifriction-rollers which bear on the tracks 52, said tracks guiding the chains of the aprons close enough together to cause the bars 50 to bind the record-strip against the bars 48 of the upper apron, said antifriction-rollers preventing the bars 48 and 49 from contacting with the track. From the feed-aprons the records pass over a rod 64 and thence to a suitable winding mechanism.

Mounted on the table at the rear end of the feed-aprons are a pair of standards 9, one of which is located near each side edge of the table. These standards support a horizontal cross-beam 8 above the record-strips, and mounted on this beam is a vertical supporting-frame 7. Pivoted at its upper end to the top of this frame is a depending frame 10, which carries the rotatable contact-bar 16, said frame forming one member of a two-part contact device. Connecting the two frame-bars 7 near their upper ends is a bar 18, of non-conducting material, and depending from this bar is a series of separated spring circuit-selector fingers 17, each of which bears on the rear side of the contact-roller and is in circuit with a double-wound electromagnet 20, which is adapted to actuate a punch-locking device or dog, as is clearly set forth in my patent hereinbefore mentioned, said series of circuit-selector fingers forming the other member of the two-part contact device. The electromagnets and the devices connected thereto constitute a punch-controlling means.

Journaled in one side of the frame 10 near its top is a stub-shaft 13^a, which is recessed

and slotted to receive one end of the spindle 13 of the perforated stencil 15, said end being formed with ribs which enter the slots and cause the spindle to rotate with the shaft. 5 The other end of the spindle 13 is loosely held in a socket 13^b, formed on the lower end of the link 13^c, which is pivoted on the side of the frame 10. To prevent a too free rotation of this spindle, flat springs 14 are pivotally secured to the frame 10 and bear at their free ends down on the ends of the spindles and act as brakes therefor and form a tension device for the stencil. These springs may be moved to one side and the spindle readily detached from its supports whenever desired. 15 Mounted in the frame 10 is a transverse cleaning-roll 25, which bears on the forward side of the contact-roller and wipes said roller clean, thus insuring a good contact between it and the circuit-selector fingers. This cleaning-roll is rotated by means of gears 26 and 27, which are carried by the swinging frame, and a smaller gear 29, secured to the inner end of a short shaft carried by the frame 7. 20 This gear meshes with the gear 27 and is driven by a belt 32, which passes around a pulley 30 on the shaft of the gear 29 and around a pulley 31 on the main shaft 2. To divert the stencil-sheet slightly forward after 25 it has passed down in engagement with the rear of the contact-roller, so as to hold it in close engagement therewith, a large loose roller 28 is mounted in the frame 10 forward of the contact-roller.

30 The two-part contact device and the punch-selecting medium or pattern-sheet constitute a punch-selecting mechanism. To normally maintain the frame 10 forward to hold the contact-roller out of engagement with the selector-fingers, springs 11 are provided, which are secured to the frame 7 and engage pins 12 on the frame 10, said springs acting to swing the frame 10 forward. On the uprights 7 are pivoted latches 66, 35 whose forward ends engage lugs 63 on the swinging frame and lock the contact-roller in engagement with the selector-fingers. Connecting these latches together is a bar 67, which is connected by a pin-and-slot arrangement to a vertical reciprocable rod 69, whose lower end is held in a suitable guide, its upper end extending to the top of the frame 7 and being provided with an operating-knob 73. This rod is normally held elevated and 40 the latches in engagement with the lugs on the frame 10 by a coil-spring 70, which surrounds said rod near its lower end. It is obvious that by pressing the rod 69 the frame 10 will be released and swung forward and 45 the contact-roller 16 will be carried away from the selector-fingers.

To automatically release this frame, when the last of the note perforations or patterns in the stencil or other punch-selecting me-

dium have passed between the roller 16 and 65 the selector-fingers the rod 69 is provided with an armature 71 above an electromagnet 72, which is in circuit with the contact-bar 16 and with a contact-finger 77, which bears on the punch-selecting sheet near the edge thereof and contacts with the bar 16 only when the end of the sheet has passed under it. It is obvious, however, that a suitable perforation may be formed in the sheet in such a position that it will permit the finger 77 to contact with the bar 16 immediately after the last note-perforation on the sheet has passed over the contact-roller, as indicated in dotted line in Fig. 6. When the end of the pattern-sheet passes under contact-finger 77 and said finger is permitted to contact with the roller 16, the magnet 72 pulls down armature 71 and causes rod 69 to release the catches which hold the frame 10. 75

From the guide-roller 28 the stencil passes 80 downward in the rear of a transverse horizontal rod 33, which is secured at its ends in the upper ends of vertical arms 34, mounted on the ends of a rock-shaft 35, this shaft being journaled in suitable standards mounted 85 on the table 1. One of the arms 34 is slotted longitudinally, and adjustably mounted in said slot is the forward end of a pitman 36. The rear end of this pitman is connected to the strap of an eccentric 37, secured on the 90 shaft 2. The movement of the eccentric is so timed that the bar 33 will begin to move rearward the moment the punches are clear of the record-blanks in moving upward and will continue this rearward movement until 95 the punches have completed their upward movement, when it will then be moved forward. From the vibrating bar 33 the stencil is carried down to and under the horizontal roller 38, which is suitably supported on the 100 table just above the records or perforated sheets 5. After passing under the roller 38 the stencil is carried forward with the record-strips and is clamped with them between the transverse gripping-bars of the feed-aprons. 105 When the forward end of the stencil has passed from between these aprons, it is secured to a hook 60 of a transverse shaft 59 and is wound thereon by means of a belt 62, which passes over a pulley 61 on the end of the 110 shaft 64 and over a pulley 63 on the shaft 43 of one of the feed-aprons. 115

The vibration of the bar 33 feeds the stencil between the selector-fingers and the contact-bar, and the movement of the eccentric 37 is timed, as described, in order that this feeding movement may be completed in advance of the feeding movement of the carrier-aprons. The movement of the cam 47, which actuates the feed-aprons, is so timed 120 that the aprons will begin to draw the record-blanks when the punches have reached the highest point in their upward movement 125

and will complete said drawing movement before the punches reach the blanks on their downstroke.

I have found in practice that this is the only safe time to feed the blanks under the punches, as there is always more or less buckle to the paper at the punches, and to start the paper while the punches are in their upward movement results very often in torn records, caused by the edges of the perforations catching on the punches. I have also found in practice that if the stencil and the record-blanks are fed synchronously during the downward movement of the punches the time is too short to permit the punch-selecting and punch-locking mechanism to properly work unless the machine be operated very slowly.

In perforating a plurality of webs of paper it is of course necessary not to begin the feed movement of the record-blanks until the instant that the punches are withdrawn from the webs on the upstroke. I have discovered it to be even preferable to avoid beginning this feed until the punches start on the return stroke, owing to the "bur" left by the punches in the paper sticking and clogging the feed by catching on the punches. All the time that the punches are moving through the superimposed webs of record-blanks—*i. e.*, while they are being withdrawn from the webs of paper—is lost so far as the means for controlling the perforating mechanism is concerned. I have discovered that by providing an auxiliary feed for the stencil that actuates the punch-controlling mechanism and by giving this a movement which is out of phase with relation to the feeding movement of the record-blank-feeding mechanism, and preferably in advance thereof, I can give the punch-controlling mechanism additional time to act, and thus be certain to set and lock the punches before the record-blanks have been fed to their new position ready to be perforated anew. Time is thus also given to permit the locked punches to be released. This improvement does away with the failure to punch some of the holes in the record-blanks, as often happened in prior machines.

In order, therefore, that the machine may be operated rapidly, I have arranged the stencil-feeding eccentric 37, as described, so that it will operate to feed the stencil in advance of the movement of the record-blanks. By this means I secure double the time for the operation of the circuit-selecting and punch-locking mechanism as for moving the record-blanks. The result of this advancement of the stencil is that the punch-locking dogs are moved into place when the punches reach the highest point in their movement. It will be understood that the rate of movement of the

stencil and the record-blanks is the same—that is, the distance moved each step is 65 equal.

I will now describe the means for detecting the imperfections in the record-blanks. The distance between the roller 38 and the point of contact between the selector-fingers 70 and the contact-bar is about the same or a trifle shorter than from said roller to the punches. The object of this is that when the stencil or pattern-sheet and records are brought together between the aprons the 75 pattern or note-perforations of the stencil will register with the corresponding note-perforation in the records. By this means the records may be compared with the stencil and imperfections noted immediately. As 80 the stencil is fed in advance of the records there will be a slightly greater length of stencil between the contact-bar and the roller 38 than there is of record-strip between the punches and said roller; but this extra length 85 of stencil is taken up in passing around the roller 28 and in extending rearward over the vibrating bar 33 when said bar is in its rearward position.

It will be noted that the pattern-sheet is 90 arranged between the eye of the observer or comparer and the record-blank so that by looking through the holes in the pattern-sheet the observer can readily detect whether the corresponding holes have been punched 95 in the stock.

In order that the stencil-sheet may be readily rewound on the roller 13, a small gear 76 is secured over the outer end of the shaft 13^a. Meshing with this gear is a large gear 74, mounted on the adjacent side of the frame 10, said large gear being provided with an operating-handle 75, by which it may be rotated.

Having thus fully described my invention, what I claim, and desire to secure by Letters Patent, is—

1. In a perforator, the combination of a punching mechanism, an electrically-operated punch-controlling means, a series of circuit-selecting fingers in circuit with the punch-controlling means, a contact for said fingers also in said circuit, means for moving a pattern-sheet in contact with the selector-fingers to actuate said fingers, and means adapted to be controlled by the pattern-sheet to automatically render the circuit-selecting means inoperative.

2. In a perforator, the combination of a punching mechanism, an electrically-operated punch-controlling means, a series of circuit-selecting fingers in circuit with the punch-controlling means, a contact for said fingers also in said circuit, means for moving a pattern-sheet in contact with the selector-fingers to actuate said fingers, and electric-

- ally-actuated means adapted to be controlled by the pattern-sheet to automatically render the circuit-selecting means inoperative.
3. In a perforator, the combination of a punching mechanism, an electrically-operated punch-controlling means, a series of circuit-selecting fingers in circuit with the punch-controlling means, a contact for said fingers also in said circuit, a punch-selecting medium or pattern-sheet, means to move said medium past the circuit-selecting fingers to bring said fingers into engagement with their contact, and means controlled by the punch-selecting medium to render the circuit-selecting fingers inoperative.
4. In a perforator, the combination of a punching mechanism, an electrically-operated punch-controlling means, a contact device comprised of two members one member being formed by a series of circuit-selecting fingers, a contact for said fingers forming the other member, means for moving a pattern-sheet in contact with the selector-fingers to actuate said selector-fingers, and means for moving one member of the contact device to render said device inoperative.
5. In a perforator, the combination of a punching mechanism, an electrically-operated punch-controlling means, a contact device comprised of two members one member being formed by a series of circuit-selecting fingers, a contact for said fingers forming the other member, means for moving a pattern-sheet in contact with the selector-fingers to actuate said selector-fingers, and means adapted to be controlled by the pattern-sheet to automatically move one member of the contact device to render the circuit-selecting means inoperative.
6. In a perforator, the combination of a punching mechanism, an electrically-operated punch-controlling means, a contact device comprised of two members one member being formed by a series of circuit-selecting fingers, a contact for said fingers forming the other member, means for moving a pattern-sheet in contact with the selector-fingers to actuate said selector-fingers, and electrically-operated means adapted to be controlled by the pattern-sheet to automatically move one member of the contact device to render the punch-selecting means inoperative.
7. In a perforator, the combination of a punch mechanism, an electrically-operated punch-controlling means, a contact device comprised of two members one member being formed by a series of circuit-selecting fingers, a contact for said fingers forming the other member, a pattern-sheet or punch-selecting medium, means for moving said medium past the circuit-selecting fingers to bring said fingers into engagement with their contact, and electrically-operated means controlled by the pattern-sheet to automatically move one member of the contact device to render the circuit-selecting fingers inoperative.
8. In a perforator, the combination of a punching mechanism, an electrically-operated punch-controlling means, a two-part contact device one member thereof being a series of circuit-selecting fingers the other member being a contact for said fingers said contact device being in circuit with the punch-controlling means, a pivoted frame carrying one member of the contact device, means for moving a punch-selecting medium past the selector-fingers to bring said fingers into engagement with their contact, and means for moving the pivoted frame to separate the members of the contact device.
9. In a perforator, the combination of a punching mechanism, an electrically-operated punch-controlling means, a two-part contact device one member thereof being a series of circuit-selecting fingers the other member being a contact for said fingers said contact device being in circuit with the punch-controlling means, a pivoted frame carrying one member of the contact device, means for moving a punch-selecting medium past the selector-fingers to bring said fingers into engagement with their contact, and electrically-operated means adapted to be controlled by the punch-selecting medium for moving the pivoted frame to separate the members of the contact device.
10. In a perforator, the combination of a punching mechanism, an electrically-operated punch-controlling means, a two-part contact device one member thereof being a series of circuit-selecting fingers the other member being a contact for said fingers said contact device being in circuit with the punch-controlling means, a pivoted frame carrying one member of the contact device, a punch-selecting medium, means for moving said medium past the selector-fingers to bring said fingers into engagement with their contacts, and electrically-operated means controlled by the punch-selecting medium for moving the pivoted frame to separate the members of the contact device.
11. In a perforator, the combination of a punching mechanism, an electrically-operated punch-controlling means, a two-part contact device one member thereof being a series of circuit-selecting fingers the other member being a contact for said fingers said contact device being in circuit with the punch-controlling means, a pivoted frame carrying one member of the contact device, means for supporting a punch-selecting medium on the pivoted frame, means for drawing said medium between the members of the contact device and electrically-operated

means controlled by the punch-selecting medium for moving the pivoted frame to separate the members of the contact device.

12. In a perforator, the combination of a 5 punching mechanism, an electrically-operated punch-controlling means, a series of circuit-selecting fingers, a pivoted frame, a contact-bar carried by said frame, means for normally holding the frame in a position to 10 separate the contact-bar from the fingers, means for locking said frame to hold the contact-bar in engagement with the fingers, means for moving a punch-selecting medium between the fingers and the contact-bar, and 15 electrically-operated means adapted to be controlled by the punch-selecting medium to release the pivoted frame-locking means.

13. In a perforator, the combination of a 20 punching mechanism, an electrically-operated punch-controlling means, a series of circuit-selecting fingers, a pivoted frame, a contact-bar carried by said frame, means for carrying a punch-selecting medium on said frame, means for normally holding the frame 25 in a position to separate the contact-bar from the fingers, means for locking said frame to hold the contact-bar in engagement with the fingers, means for moving the punch-selecting medium between the fingers and 30 the contact-bar, and electrically-operated means adapted to be operated by the punch-selecting medium to release the pivoted frame-locking means.

14. In a perforator, the combination of a 35 punch mechanism, an electrically-operated punch-controlling mechanism, a series of circuit-selecting fingers, carried by a stationary frame, a swinging frame pivoted to said stationary frame and carrying a contact-bar, a 40 locking means to hold said frame and maintain the contact-bar in engagement with the selecting-fingers, and means for moving a punch-selecting medium between the fingers and the contact-bar.

15. In a perforator, the combination of a 45 punch mechanism, an electrically-operated punch-controlling mechanism, a series of circuit-selecting fingers, carried by a stationary frame, a swinging frame pivoted to said stationary frame and carrying a contact-bar, a 50 locking means to hold said frame and maintain the contact-bar in engagement with the selecting-fingers, a reciprocable rod connected to the locking means and carrying an armature, an electromagnet adapted to act 55 on said armature and move said rod, a contact-finger in circuit with said magnet and adapted to bear on the contact-bar, means for electrically connecting said bar to the 60 magnet, and means for moving a punch-selecting medium between the contact-finger and the bar.

16. In a punch-selecting mechanism, the combination of a stationary frame, a series of

selector-fingers carried thereby, a swinging 65 frame, a spring for normally holding said frame away from the stationary frame, means for locking the swinging frame to the stationary frame, means for moving a punch-selecting medium between the fingers and 70 the contact-bar, and electrically-operated means controlled by the punch-selecting medium for automatically releasing the locking means of the swing-frame.

17. In a perforator, the combination of a 75 punching mechanism, an electrically-operated punch-controlling means, means for intermittently feeding the record-blanks to the punching mechanism, a circuit-selecting contact device, a punch-selecting medium, means 80 for intermittently feeding said punch-selecting medium through the contact device, said feeding means operating in advance of the record-blank-feeding device.

18. In a perforator, the combination of a 85 punching mechanism, an electrically-operated punch-controlling means, means for intermittently feeding the record-blanks to the punching mechanism, a circuit-selecting contact device, a punch-selecting medium, a vi- 90 brating feeding device for intermittently feeding said punch-selecting medium through the contact device, said feeding means operating in advance of the means for feeding the record-blanks.

19. In a perforator, the combination of a reciprocating punch-carrying frame, an electrically-operated punch-controlling means, a step-by-step-feeding mechanism for the record-blanks, means for operating this feeding 100 mechanism while the punch-frame is moving toward the record-blanks, a circuit-selecting medium, and a step-by-step-feeding device for feeding said punch-selecting medium through the contact device while the punch-frame is moving away from the record-blanks.

20. In a perforator, the combination of a 105 punching mechanism, an electrically-operated punch-controlling means, means for intermittently feeding the record-blanks to the punching mechanism, a circuit-selecting contact device, a punch-selecting medium, means for intermittently feeding said punch-selecting medium through the contact device, said feeding means operating in advance of the 115 record-blank-feeding means, and means for leading the punch-selecting medium from the contact device into the record-blank-feeding device to cause said medium to move with the records after it has passed through the 120 contact device.

21. In a perforator, the combination of a 125 punching mechanism, means for intermittently feeding a record-blank to the punching mechanism, a contact device, means for intermittently feeding a punch-selecting pattern-sheet or medium through said contact device, and means for causing the punch-se-

- lecting sheet to progressively register with the record, whereby the record may be compared with the pattern-sheet.
22. In a perforator, the combination of a punching mechanism, means for intermittently feeding a record-blank to the punching mechanism, a contact device, means for intermittently feeding a perforated stencil through the contact device, and means for bringing the stencil after it has passed the contact device into contact with the perforated record to cause the perforations in the stencil to register with the corresponding perforations in the record.
23. In a perforator, the combination of a punch mechanism, means for intermittently feeding a record-blank to the punch mechanism, a contact device above the punch mechanism, means for intermittently feeding a perforated stencil through the contact device, means for bringing the stencil down into contact with the record to cause the perforations in the stencil to register with the corresponding perforations in the record, the superposed record and stencil passing through the record-blank-feeding mechanism in close contact.
24. In a perforator, the combination of a punch mechanism, means for intermittently feeding a record-blank to the punch mechanism, a contact device, a stencil-roll support, a tension device for the stencil, means for bringing the stencil into the record-feeding means, a vibrating rod engaging the stencil between the contact device and the record-blank-feeding device, means for moving said rod in one direction to feed the stencil through the contact device during the dwell of the record-feeding device and to move said bar in the other direction to slack the stencil when the record-feeding device operates to feed the record and take up the slack in the stencil-sheet.
25. In a stencil-feeding means for perforating-machines the combination of a support, a contact device, a tension device for the stencil, means for gripping the stencil after it has passed the contact device, a transverse bar adapted to engage the stencil between the contact device and the gripping means, means for moving said bar in one direction to pull the stencil through the contact device and in the other direction to slack said stencil, and means for intermittently moving the gripping device to take up the slack in the stencil.
26. In a perforator, the combination of a driving-shaft a punch-carrying frame reciprocated by said shaft, a stencil-support, a contact device, an apron-feed for moving a record-blank in a step-by-step manner under the punch-carrying frame, means operated by the main shaft for moving said apron-feed during the downward movement of the punch-carrying frame, a vibrating device for feeding a stencil through the contact device 65 in a step-by-step manner, and means for actuating said device from the main shaft during the upward movement of the punch-carrying frame to feed the stencil through the contact device while the apron-feed is at rest and to slack said stencil when the apron-feed is operated.
27. In a stencil-feeding means for perforating-machines the combination of a support, a tension device for the stencil, a contact device adapted to be actuated by the movement of the stencil therethrough, means for holding the stencil after it has passed the contact device, means for intermittently moving the stencil through the contact device, and means for moving the stencil-holding means after each movement of the feeding means to take up the slack in the stencil.
28. In a stencil-feed the combination of a support, a series of selector-fingers, a contact-bar, means for moving a stencil between the fingers and the bar, a cleaning device for cleaning the contact-bar, and means for operating said cleaning device.
29. In a stencil-feed the combination of a support, a series of selector-fingers, a rotary contact-bar, means for moving a punch-selecting medium between the fingers and the bar, a cleaning-roll in contact with the contact-bar, and means for rotating said cleaning-roll.
30. In a stencil-feed the combination of a support, a series of selector-fingers, a contact-bar, means for removably mounting a roll stencil-roll, a brake device for said roll, means for moving a stencil between the fingers and the contact-bar, and a rewinding mechanism adapted to rotate the stencil-roll.
31. In a record-blank-feeding mechanism 105 for perforating-machines, the combination of a support, a pair of endless feed-aprons having their feeding-surfaces parallel and in proximity to each other, transverse rigid gripping-bars carried by each apron, rigid guides for the ends of said bars whereby the aprons are brought together to cause the rigid gripping-bars to grip the record-blank, and means for giving the aprons a synchronous intermittent movement.
32. In a record-blank-feeding mechanism, the combination of a support, a pair of endless feed-aprons, rigid transverse gripping-bars secured to one of said aprons, cylindrical gripping-bars carried by the other apron, means for rotatably supporting the cylindrical bars, rigid guides for the aprons whereby the bars are brought together to grip the record-blank, and means for giving the aprons a step-by-step movement.
33. A record-blank guide consisting of parallel bars between which the blanks pass, means for simultaneously and synchro-

nously adjusting said bars toward or from each other, and a removable bed-piece supported by said bars.

34. In a perforator the combination of a punch-carrying frame, means for reciprocating it, a record-blank guide consisting of a pair of parallel guide-bars to guide the blanks to the punch-carrying frame and a pair of similar guide-bars to guide the records from the said frame, internally-threaded lugs carried by each bar the lugs on one bar being threaded in one direction while the lugs on the opposite bar are threaded in the opposite direction, a series of shafts passing through corresponding lugs on opposite bars, gears on corresponding ends of these shafts, a shaft and a series of gears carried thereby and adapted to engage the gears on the threaded shafts to rotate therein in the same direction.
35. A support for a plurality of record-blank rolls consisting of a pair of parallel side bars provided with recesses in their upper edges, a series of transverse shafts removably mounted in said recesses and carrying the record-blanks, in combination with a punching mechanism, and means for holding the record-blanks in close contact one above the other as they pass through the punching mechanism, and means for drawing the record-blanks through the punching mechanism in a step-by-step movement.
36. A record-blank guide for a perforating machine, consisting of parallel bars, means for adjusting said bars toward and from each other, and a removable bed-piece supported by said bars.

37. In a perforating-machine the combination of a perforating mechanism, a record-blank guide for guiding the superimposed webs to be perforated through the perforating mechanism, consisting of two pairs of parallel bars, the bars of each pair being arranged in alinement, and means for simultaneously and synchronously adjusting each pair of bars toward and from each other.

38. In a perforating-machine, the combination of a perforating mechanism, means for feeding the record-blanks to the perforating mechanism, means for controlling the perforating mechanism, and means for preserving an out-of-phase relation between the time of actuation of the controlling means and the feeding means for the record-blanks, substantially as described.

39. In a perforating-machine, the combination of a perforating mechanism, controlling mechanism for the perforators, including a pattern-sheet, and means for giving the pattern-sheet a feed movement which is out of phase with the feed movement of the record-blanks, substantially as described.

nation of a perforating mechanism, controlling mechanism for the perforators, including a pattern-sheet, and means for giving the pattern-sheet a feed movement which is out of phase with the feed movement of the record-blanks, substantially as described.

40. In a perforating-machine, the combination of a perforating mechanism, means for controlling the perforating mechanism, means for feeding the record-blanks to the perforating mechanism, and means for actuating the controlling means in advance of the actuation of the means for feeding the record-blanks, substantially as described.

41. In a perforating-machine, the combination of a perforating mechanism, means for controlling the perforating mechanism electrically, means for feeding the record-blanks to the perforating mechanism, and means for energizing the electrical controlling means in advance of the actuation of the means for feeding the record-blanks, substantially as described.

42. In a perforating-machine, the combination of a perforating mechanism, means for controlling the perforating mechanism electrically, means for feeding the record-blanks to the punches during the movement of the punches toward the record-blanks, and means for energizing the controlling means for the punches during the movement of the punches away from the record-blanks, substantially as described.

43. As a means for detecting the imperfections in music-record blanks, the combination of a pattern-sheet arranged between the eye of the comparer and the record-blanks, and means for associating therewith the music-record blank to be compared, substantially as described.

44. As a means for detecting the imperfections in music-record blanks, the combination of a pattern-sheet arranged between the eye of the comparer and the record-blanks, and means for associating in registering contact therewith the music-record blanks to be compared, substantially as described.

Signed at Brooklyn, in the county of Kings and State of New York, this 20th day of April, A. D. 1901.

GEORGE HOWLETT DAVIS.
